UNITED STATES PATENT OFFICE.

HORACE PALMER, OF LEBANON, CONNECTICUT.

ROTARY CLOTHES-DRIER.

SPECIFICATION forming part of Letters Patent No. 252,506, dated January 17, 1882.

Application filed October 24, 1881. (Model.)

To all whom it may concern:

Be it known that I, HORACE PALMER, of Lebanon, in the county of New London and State of Connecticut, have invented a new and 5 useful Improvement in Rotary Clothes-Driers, of which the following is a full, clear, and exact description.

Reference is to be had to the accompanying drawings, forming part of this specification, in 10 which similar letters of reference indicate corresponding parts in all the figures.

Figure 1 is a perspective view of my improvement, shown as extended for use. Fig. 2 is a side elevation of the upper part of the 15 same, shown as folded. Fig. 3 is a sectional plan view of the upper part of the same, taken through the line $x-x$, Fig. 2.

The object of this invention is to provide rotary clothes-driers, constructed in such a manner that they can be folded compactly for storage and transportation.

The invention consists in a rotary clothes-drier constructed with a slotted pivoted post, bars hinged to the said post carrying the 25 clothes-lines, and having hinged to them the upper ends of connecting-bars, the lower ends of which are hinged to crossed bars placed in the slots of the posts, and held down by a lever to put the clothes-lines under tension, and 30 also in the combination, with the slotted post and the lever having ratchet-teeth upon its upper side, of a pawl hinged to the said post, whereby the lever is locked in place holding the clothes-lines under tension, as will be hereinafter fully described.

A represents a base or pedestal, to which is pivoted the lower end of a post, B. In the post B are formed two longitudinal slots, at right angles with each other, extending from 40 the upper end of the said post nearly to its lower end, and dividing the upper part of the said post into four parallel arms.

To and between the upper ends of the arms of the post B are hinged the inner ends of four 45 bars, C.

To each of the bars C, at a little distance from its inner end, is hinged the upper end of a bar, D, the lower end of which is hinged to an arm of the crossed bars E. The two bars 50 E pass through the slots of the post B, and

cross and are secured to each other at their centers and at the center of the said post.

To the hinged arms C are attached the clothes-lines F, upon which the clothes are hung to be dried, and which are designed to 55 be made of such a length that the bars C cannot swing down quite to a horizontal position.

The upper crossed bar E has a rounded projection or rise in its middle part to serve as a fulcrum to the lever G, which passes through 60 one of the slots of the post B. Through the end of the lever G is passed a pin, H, the ends of which project to rest against the rear side of the post B, and beneath a pair of pins, I, attached to the said post B. Two or more 65 pairs of pins, I, are attached to the post B at different heights for the ends of the pin H to rest against, so that the lever G can be adjusted as the tautness of the clothes-lines F may require. With this construction, when 70 the bars C have been lowered as low as their own weight will carry them, the cross-pin H of the lever G is placed beneath a pair of the pins I, and the free end of the said lever is pressed downward, forcing the crossed bars E 75 downward and drawing the bars C toward a horizontal position until the clothes-lines F have been put under the desired tension.

To the post B, at a little distance from its upper end, is hinged a pawl, J, the engaging 80 end of which rests upon ratchet-teeth K, formed upon or attached to the upper side of the lever G, to hold the said lever G, and with it the bars C, securely in place.

When the clothes-drier is to be folded, the 85 cross pin H of the lever G is hung upon a pair of pins, L, attached to the upper part of the post B. The outer ends of the bars C can then be swung upward and inward, which movement folds the bars C and D compactly together 90 around the post B, as shown in Fig. 2.

Having thus fully described my invention, I claim as new and desire to secure by Letters Patent—

1. A rotary clothes-drier constructed substantially as herein shown and described, and consisting of the slotted pivoted post B, the hinged bars C, carrying the clothes-lines F, the connecting-bars D, the crossed bars E, the lever G, and detaining device, as set forth. 95

2. In a rotary clothes-drier, the combination, with the slotted post B, the lever G, and detaining devices, of the hinged bars C, the connecting-bars D, and the crossed bars E, the upper one of which has a rounded projection or rise in the middle of its length, substantially as and for the purpose set forth.

3. In a rotary clothes-drier, the combination, with the slotted post B, provided with pins I,

the hinged bars C, the connecting-bars D, and the crossed bars E, of the lever G, provided with the ratchet-teeth K, and the pawl J, substantially as and for the purpose set forth.

HORACE PALMER.
